DESIGN FOR A CLOSURE CAP

Clarence W. Fuller, Yonkers, N. Y.

Application October 11, 1948, Serial No. 149,069

Term of patent 14 years

(Cl. D58—26)

To all whom it may concern:

Be it known that I, Clarence W. Fuller, a citizen of the United States, residing at Yonkers, in the county of Westchester and State of New York, have invented a new, original, and ornamental Design for a Closure Cap, of which the following is a specification, reference being had to the accompanying drawing, forming a part thereof.

Fig. 1 is a front elevational view, partly in section, of a closure cap, showing my new design.

Fig. 2 is a top plan view thereof.

Fig. 3 is a bottom plan view thereof.

Fig. 4 is a side elevational view as viewed from the left of Fig. 1, with the stopper member in closing position.

Fig. 5 is a similar view, but with the stopper element in open position.

Fig. 6 is a top plan view similar to Fig. 2, but with the stopper element removed for the purpose of clarity.

The dominant feature of the design resides in the portions shown in full lines.

I claim:

The ornamental design for a closure cap, substantially as shown and described.

CLARENCE W. FULLER.
